FLASK.

No. 18,932.

UNITED STATES PATENT OFFICE.

LE ROY W. FAIRCHILD, OF NEW YORK, N. Y.

DESIGN FOR A FLASK.

SPECIFICATION forming part of Design No. 18,932, dated February 19, 1889.

Application filed January 21, 1889. Serial No. 297,098. Term of patent 3½ years.

To all whom it may concern:

Be it known that I, LE ROY W. FAIRCHILD, a citizen of the United States, residing at New York, in the county of New York and State 5 of New York, have invented a new and original Design for a Flask, of which the following is a specification.

My invention consists of a design for a pocket-flask.

10 The accompanying photograph is a face or side view of a flask showing the design.

The design consists, first, in the shape or configuration of the body of the flask, and, second, in the ornamentation thereof. As 15 shown in the accompanying photograph, the body of the flask is wider near its top than at its bottom, the two edges between these points being formed of two slight curves, which are united at their meeting ends by a slight projection, which imparts to the outline or edges 20 of the body a curved and wave-like form. The shoulders or corners at top and bottom are rounded, and the bottom is formed with curves and a central projection similar to that of the edges, as shown, thus giving to the body 25 as a whole, when viewed from the face or side, an ornamental and pleasing appearance. The ornamentation consists of the representation of the head of a female, the face being shown in what is usually termed a "quartering 30 view," and which is represented as being in the midst of a cluster of flowers, the latter appearing in a mass below the chin and extending up alongside of and partially behind the head, as clearly shown in the photograph. 35

The two features of outline and ornamentation together form a beautiful design for a flask.

What I claim is—

The design for a flask, substantially as 40 shown and described.

In witness whereof I hereunto set my hand hand in the presence of two witnesses.

LE ROY W. FAIRCHILD.
